[57] **CLAIM**

The ornamental design for a wing type sailing yacht, as
shown and described.

DESCRIPTION

FIG. 1 is a top and side perspective view of a wing type
sailing yacht showing my new design;

FIG. 2 is a side elevational view thereof, the opposite
side elevational view being a mirror image of that
shown;

FIG. 3 is a front elevational view thereof;

FIG. 4 is a top plan view thereof;

FIG. 5 is a front elevational view of a second embodi-
ment of the wing type sailing yacht;

FIG. 6 is a bottom plan view of FIGS. 1 and 5; and,

FIG. 7 is a rear elevational view of FIG. 5.

The sole difference between the first embodiment
and second embodiment being in that the first embodiment
have ribs on the mast.

FIG. 1

FIG. 2

FIG. 3

FIG. 4

FIG. 5

FIG. 6

FIG. 7
